CLAIM

The ornamental design for an anchoring bracket, as shown and described.

DESCRIPTION

FIG. 1 is a perspective view of an anchoring bracket showing my new design;

FIG. 2 is top plan view thereof;

FIG. 3 is a left side elevational view thereof;

FIG. 4 is a front elevational view thereof;

FIG. 5 is a right side elevational view thereof;

FIG. 6 is a bottom plan view thereof;

FIG. 7 is a perspective view of a second embodiment of the present invention;

FIG. 8 is top plan view thereof with respect to FIG. 10;

FIG. 9 is a left side elevational view thereof;

FIG. 10 is a front elevational view thereof;

FIG. 11 is a right side elevational view thereof;

FIG. 12 is a bottom plan view thereof;

FIG. 13 is a perspective view of a third embodiment of the present invention;

FIG. 14 is top plan view thereof with respect to FIG. 16;

FIG. 15 is a left side elevational view thereof;

FIG. 16 is a front elevational view thereof;

FIG. 17 is a right side elevational view thereof; and,

FIG. 18 is a bottom plan view thereof.
